UNITED STATES PATENT OFFICE.

JOHN P. NISSEN, OF PHILADELPHIA, PENNSYLVANIA.

DESIGN FOR A STOCKING.

Application filed July 31, 1924. Serial No. 10,334. Term of patent 14 years.

To all whom it may concern:

Be it known that I, JOHN P. NISSEN, residing at Philadelphia, in the county of Philadelphia and State of Pennsylvania, have invented a new, original, and ornamental Design for a Stocking, of which the following is a specification, reference being had to the accompanying drawing, forming a part thereof.

The figure is a side elevation of a stocking showing my new design. The upper portion 1 is of a different color from the foot 2, the latter being preferably a single

solid color, shown as broken away by reason of the requirements of the Patent Office against illustrations in solid color. The juncture between the two colors at the heel consists of a series of steps 3 formed partly of both colors. The line of juncture along the main body of the foot is also partly of both colors. The toe cap has side stepped formation formed partly of the two colors.

I claim:

The ornamental design for a stocking, as disclosed.

JOHN P. NISSEN.
